LIQUID SOAP DISPENSER

William J. Dobkin, Jackson Heights, N. Y., as
signor to Mac. B. Feinson, New York, N. Y.

Application July 6, 1946, Serial No. 681,691

13 Claims. (Cl. 299—84)

1

This invention relates to a machine for dispensing liquid soap. It is an object of this invention to provide a soap dispensing mechanism which will effectively deliver liquid soap in the form of a soft lather, without danger of leaking or clogging.

It is a further object to provide a device of the character described in which all of the operating parts may be easily disassembled and cleaned, and which may be easily reassembled in operating condition with simple tools, and yet in which the parts will be held firmly in operative position when so assembled.

It is a further object to provide a lather forming dispenser having means for pumping liquid soap and means for pumping air for mixture with the soap, in which the pumping mechanisms are connected to be operated by movement of a single plunger, but in which it is not necessary to maintain the pumping mechanisms in exact alignment or exact relation, so that larger tolerances in construction may be permitted without danger of the parts binding, and without impairing the perfection of the operation, thus reducing the cost of manufacture.

This invention is particularly intended for use in connection with the invention of my co-pending application Serial Number 681,692 filed of even date herewith, but its general structure is capable of wide application, as will be clear from the description.

The invention accordingly comprises a device possessing the features, properties and the relation of elements which will be exemplified in the article hereinafter described and the scope of the application of which will be indicated in the claims.

For a fuller understanding of the nature and objects of the invention, reference should be had to the following detailed description taken in connection with the accompanying drawings, in which:

Figure 1 is a side elevation, partly in section, of a dispenser such as is disclosed in my co-pending application, embodying the invention of this application. Figure 1A is a detail.

Figure 2 is a central section through the pumping mechanism shown in the upper part of Figure 1.

Figure 3 is a view similar to Figure 2, but with the plunger partly pushed in.

Figure 4 is a section along the line 4—4 of Figure 2.

Referring now to the drawings, and particularly to Figure 1, as shown in said co-pending appli-

cation, the numeral 10 represents a wall plate adapted to be attached to a wall in any convenient manner, as for example by screws not shown, and detachably attached to the upper end of this plate is a head assembly 11, having a downwardly extending hood 12, into which may be inserted the upper end of a container 13, which may be in the form of a bottle, preferably having a shoulder surrounding the neck which fits closely into a downwardly facing opening 14 in the lower face of hood 12. The bottle is held in place by a locking assembly 15 attached to the bottom end of the plate 10.

Referring now to the head assembly 11, there is provided a plate 16 having rearwardly extending side flanges 17 and an upper flange 18. The rear face of the hood portion is of substantially the same size and shape as the plate 16, and the edges of it surround and are attached to the flanges 17 and 18. This plate 16 is provided with a vertical channel 19 terminating in an opening or recess 20 extending through the upper flange 18. A latching plate or strap 21 rests within the channel 19 and has its upper end caught in the opening 20.

This plate 21 is provided with a non-circular opening 23 to receive the outer end of the soap pumping cylinder as will be hereinafter described. The plate 21 has a hook 25 bent backwardly from its surface in position to engage the upper end of the plate 10 as shown at 26.

The hood 12, as here shown, has the general shape of a quadrant of a cylinder, which has its central upper portion pressed out as shown at 29 to form a partial horizontal cylinder providing an outer circular outwardly facing vertical opening, surrounded by a flange 30.

The pump mechanism comprises a casing 31 in which there operates a pump plunger 32, having a soap discharge port 33. The pump casing 31 fits closely within the opening defined by the flange 30, and inside the hood has its wall expanded outwardly to form a shoulder 34 adapted to fit against said flange, and from thereon continues cylindrically to form an extension of larger diameter as shown at 35. A pump cylinder 36 has at its front end a flange 38 adapted to bear against a washer 39 which in turn bears against the rear face of the shoulder 34, thus closing the outer end of casing 31. This flange 38 contains projecting pins 40 and 41 which extend into openings in tabs 42 and 43 projecting outwardly from the extension 35, and at least one of these tabs is sufficiently resilient to enable the pins 40—41 to

be snapped into place holding the parts in assembled position.

The inner end of the cylinder 36 terminates in a non-circular projection 37 fitting within the opening 23 in the plate 21, this projection being designed by its non-circular shape to keep the cylinder from rotating out of position. At the base of this projection, the cylinder is provided with a shoulder 44 adapted to bear against the plate 21 at the periphery of the opening 23. The length of the cylinder 36 is such that with the parts in assembled position, as shown, the plate 21, after being latched into the opening 20 and brought into engagement with the end of the cylinder 36 and drawn into place by the screw 22 will exert firm pressure to press the cylinder flange 38, the washer 39 and the shoulder 34 firmly together, and hence effect a good seal between the parts.

A cylinder 36 has a central bore 45 concentric with the casing 31, and communicating with the interior of the container 13 by a tube 46 which extends to the bottom of the container. This tube is provided with a check valve 47 which may be conveniently formed as follows:

A nipple 48 may be threaded into the lower end of the tube 46 having its upper end formed to serve as a valve seat in cooperation with a ball 49. The upward movement of the ball may be limited by pinching the tube as shown in 46a.

We will now proceed to describe the plunger elements of the pump, comprising body 32 and associated parts. This body 32 is cylindrical in form, sliding in a bearing 50 in casing 31. Being closed at its outer end by a head 51, carrying the port 33 above referred to, the plunger body 32 is prevented from rotating by an extension or boss 52 which rides in a longitudinal slot of bearing 50.

Into the inner end of the tube 32, there is screwed a flanged nipple 53, and between the flange of this nipple and the cylinder there is held a washer 54 which fits the cylindrical interior of the casing 31. A channel-shaped washer 55 fits within the washer 54, and against the flange of the nipple 53, and this washer is designed to contain and center the end of a spring 56, the other end of which bears against the washer 39. Thus the plunger 32 is urged outwardly by the spring 56.

A sleeve 57 slides within a central opening 58 in washer 39, and within this sleeve there is carried the stem 60 of a pin having a head 61 and carrying a washer 62 adapted to bear against the end of the sleeve 57. The stem 60 is provided with a small fluted section 63 so that the pin 60 is kept centered within the sleeve 57 but at the same time access is afforded between the bore 45 and the interior of the bore of the sleeve 57 when the pin projects slightly to the left out of the tube 57 as shown in Figure 3. The other end of the stem 60 is provided with an opening 64 through which there may be inserted a pin 65, but this pin 65 is spaced so far from the head 61 as to provide a lost motion between the sleeve 57 and the washer 62.

The pin 65 is of a length to fit within the interior of the channel portion of the washer 55 so as to be held in place against lateral displacement thereby, and this pin is engaged on the one side by the face of washer 55 and on the other side by the end face of nipple 53.

The washer 55 has an inner bore as shown at 66 to receive the opposite end of the sleeve 57, and thus has a relatively close fit about the sleeve, 70

in order to keep the latter properly centered. As has been disclosed, the pin 65 spaces the washers 53 and 55 leaving a small chamber between them which is in free communication with the interior of the member 53. Openings 67 through washer 55 afford communication between this chamber and the interior of casing 31.

The outer wall of washer 55 is substantially cylindrical, extending toward the washer 39 and thus serves not only to arrest but also to cushion the inward movement of the plunger.

With the above construction, it will be clear that with the parts shown in the position in Figure 2, if the plunger 32 is pushed inwardly, the first part of the movement will push the stem 60 and washer 62 inwardly into the bore 45, without moving the sleeve 57 until the lost motion has been taken up. Thus an opening is provided between the washer 62 and the end of sleeve 57 which permits soap to be admitted to the interior of the bore of tube 57 surrounding the pin 60, and this soap is forced completely through the sleeve 57 and delivered into the interior of the nipple 53.

On the return stroke, actuated by the spring 56, the plunger 32 moves outwardly carrying the stem 60 and washer 62, but it does not move sleeve 57 until the washer 62 comes into contact with the end of the sleeve 57, thereby closing all communication between the bore 45 in the cylinder 36, and the interior of the sleeve 57. During all the rest of the outward stroke, as the sleeve 57 slides out of the bore 45, soap is drawn up into the bore 45 through the valve 49, at the same time air is drawn into the interior of the plunger 32 through the port 33 to make up for the displacement of the piston washer 54 within bore 31.

This sucking of air into the interior is for the purpose of converting the soap into a lather before it is dispensed, and to accomplish this result there is provided within the cylinder 32 a device 69 for insuring a very fine admixture of the air and soap to create such a lather. The mechanism here shown for that purpose is simple to manufacture, is efficient in operation, and is very easily cleaned. It comprises a core rod 70 upon which is wound in the form of a helix a coil spring 71, the ends 72 of which are attached to the core 70. In practice it is perfectly feasible to solder the spring to the core 70 throughout its length, since as the coils extend outwardly from the core rod, they spread from each other and the adjacent coils are not soldered to each other except at the core itself. This form of construction has proved very satisfactory in converting the mixture of air and liquid soap into a fine lather, while at the same time it has been particularly free from clogging. Moreover in any servicing of the dispenser the entire spring assembly may be readily washed clean for re-use.

The valve is assembled as follows: The wall bracket 10 is first cemented or otherwise attached to the wall at the point desired. The mechanism is then assembled by inserting the device 69 within the plunger 32, these parts being held in place by screwing in nipple 53. Next the sleeve 57 is inserted through the washer 39, and the pin 60 is inserted in the sleeve. The spring 56 is now inserted over the sleeve against the washer, and the channel-shaped washer 55 is inserted over the spring and by means of it the spring is compressed far enough to expose the opening in the end of the rod 60. When the pin 65 is inserted through the stem, the spring may be released so that the washer 55 prevents dis-

placement of the pin 65, yet the pin 65 holds the washer in place against the tension of the spring 56.

The cylinder 36 now has its flange 38 pressed against the washer 39 on the interior of the extension 35 of casing 31 until the pins 40-41 fit into the openings in the tabs 42-43. This engagement holds the pumping mechanisms together so that they be thereafter handled as a unit in the further assembly.

The pumping mechanisms may now be inserted through the flange 30 of the hood and the latching plate 21 caught into the opening 20 and the non-circular opening therein made to register with the non-circular projection on the end of the cylinder. The screw 22 may be then inserted in place. The dimensions of the parts are such that as screw 22 is tightened, flange 38, washers 39 and the shoulder 34 will be brought into firm engagement to prevent leakage.

The hood 12 may now be assembled on the wall plate by hooking the hook 25 over the top edge of the plate and inserting the screws 27. Thereafter the soap container may be pushed into the bottom of the hood and held in place by the locking device 15.

As will be seen from the figure, a groove 75 is provided in the head 51 to separate the port 33 from the button 76 in order to prevent seepage of soap onto the button, which would make it wet and slippery.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

I claim:

1. A soap dispenser comprising a casing having a cylindrical bore having a free end, a tube slideable within said bore carrying a plunger washer adapted to engage the interior of said bore, a shoulder within the free end of said casing, a bearing washer having a central bore adapted to fit against said shoulder and a member having a central bore comprising a cylinder, a piston mechanism slideable within said bore and cylinder, a spring compressed between said bearing washer and said plunger washer, and a spring catch mechanism for holding said bearing washer against said shoulder.

2. A soap dispenser comprising a casing having a cylindrical bore, having a free end, a tube slideable within said bore carrying a plunger washer adapted to engage the interior of said bore, a shoulder within the free end of said casing, a bearing washer having a central bore adapted to fit against said shoulder and a member having a central bore comprising a cylinder, said cylinder having a flange adapted to be held flat against the bearing washer, a sleeve slideable within the bore of said bearing washer, a stem slideable within said sleeve and having a head, said sleeve being slideable with said stem but with a lost motion, and a spring catch mechanism for holding said bearing washer against said shoulder.

3. A device of the character described comprising a cylinder having a concentric bore in

one end thereof, a sleeve having a sliding fit within said bore, a stem sliding within said sleeve to afford a channel for liquid soap between them, a head fixed to the end of said stem within said bore in position to close the end of said sleeve, and means upon the other end of said stem to cause said sleeve to move with said stem but with lost motion between them, a valve connection adapted to connect said cylinder with a source of soap supply, and means to move said stem.

4. A device of the character described comprising a cylinder having a concentric bore in one end thereof, a sleeve having a sliding fit within said bore, a stem sliding within said sleeve to afford a channel for liquid soap between them, a head fixed to the end of said stem within said bore in position to close the end of said sleeve, and means upon the other end of said stem to cause said sleeve to move with said stem but with lost motion between them, a valve connection adapted to connect said cylinder with a source of soap supply, a casing coaxial with said cylinder having a plunger therein, said plunger being connected to move said stem, the interior of said casing being connected to the interior of said sleeve, said plunger being provided with a discharge channel and a discharge port through which soap may be dispensed when said plunger is pressed into said casing.

5. A device of the character described comprising a cylinder having a concentric bore in one end thereof, a sleeve having a sliding fit within said bore, a stem sliding within said sleeve to afford a channel for liquid soap between them, a head fixed to the end of said stem within said bore in position to close the end of said sleeve, and means upon the other end of said stem to cause said sleeve to move with said stem but with lost motion between them, a valve connection adapted to connect said cylinder with a source of soap supply, a casing coaxial with said cylinder having a plunger therein, said plunger being connected to move said stem, the interior of said casing being connected to the interior of said sleeve, said plunger being provided with a discharge channel and a discharge port through which soap may be dispensed when said plunger is pressed into said casing, a lather forming device within the discharge channel in said plunger.

6. A soap dispensing device comprising a casing, a hollow thrust member slideable in said casing having an open end, a lather forming element insertible in said thrust element through said open end, a plunger washer of larger diameter than said thrust element, concentric therewith to give a sliding fit within said casing, detachable means for attaching said washer to said thrust element, said casing having an extension of larger diameter to provide a shoulder, a bearing washer adapted to lie against said shoulder to close the end of said casing and having a concentric bearing, a cylinder having a peripheral flange adapted to fit within said extension and against said bearing washer, and means for holding said flange in place within said extension.

7. A soap dispensing device comprising a casing, a hollow thrust member slideable in said casing having an open end, a lather forming element insertible in said thrust element through said open end, a plunger washer of larger diameter than said thrust element, con-

centric therewith to give a sliding fit within said casing; detachable means for attaching said washer to said thrust element, said casing having an extension of larger diameter to provide a shoulder, a bearing washer adapted to lie against said shoulder and having a concentric bearing, a cylinder having a peripheral flange adapted to fit within said extension and against said bearing washer; and means for holding said flange in place within said extension, a plunger connected to said thrust rod and slideable within said bearing washer, into and out of said cylinder, and including a valve for opening communication between said cylinder and the interior of said casing on an inward thrust of said thrust member, and to close said communication during the outward thrust, and a tube adapted to be connected to a source of liquid soap, and to said cylinder to admit soap to the interior of said cylinder during an out-stroke of said thrust member.

8. A soap dispensing device comprising a casing, a hollow thrust member slideable in said casing having an open end, a lather forming element insertible in said thrust element through said open end, a plunger washer of larger diameter than said thrust element, concentric therewith to give a sliding fit within said casing, detachable means for attaching said washer to said thrust element, said casing having an extension of larger diameter to provide a shoulder, a bearing washer adapted to lie against said shoulder and having a concentric bearing, a cylinder having a peripheral flange adapted to fit within said extension and against said bearing washer, and means for holding said flange in place within said extension, a plunger connected to said thrust rod and slideable within said bearing washer, into and out of said cylinder, a sleeve slideable within said bore in said bearing washer, a stem loosely slideable within said sleeve and connected to said thrust member, a valve head upon one end of said stem to close the end of said sleeve within said cylinder, and a pin extending through the other end of said stem in position to engage the other end of said sleeve but with a lost motion whereby the sleeve is closed by said valve head upon movement of the sleeve out of the cylinder, and is open during the motion thereof into the cylinder to permit the passage of soap into said casing, and a spring compressed between said bearing washer and said plunger.

9. In a soap dispenser, a pumping mechanism comprising a casing having an outlet in one end and a concentric bore in the other end thereof, a sleeve having a sliding fit in said bore, a stem loosely sliding within said sleeve, and having a head movable to a position to close the end of said sleeve; and a pin extending through the other end of said stem so spaced with regard to said head as to provide lost motion between said stem and said sleeve; means to reciprocate said pin.

10. In a soap dispenser, a pumping mechanism comprising a casing having an outlet in one end and a concentric bore in the other end thereof, a sleeve having a sliding fit in said bore, a stem loosely sliding within said sleeve, and having a head movable to a position to close the end of

said sleeve; and a pin extending through the other end of said stem so spaced with regard to said head as to provide lost motion between said stem and said sleeve, means to reciprocate said pin, said stem having a fluted end adjacent to said head to maintain said head concentric with said sleeve while affording passage for fluid between said stem and said sleeve.

11. A soap dispensing mechanism including a casing having an open end and a bore in the other end, a plunger slideable in said bore and having a detachable plunger head insertible through the open end of said casing, a washer having a central bore for closing the open end of said casing, a soap pumping mechanism slideable in said bore, having an operating stem extending into said bore, a pin within said casing passing through said stem, a washer adapted to bear against said plunger and holding said pin in place and held in place by said pin, a compression spring held between said first mentioned washer and said second mentioned washer, and a catch for holding said first mentioned washer in the open end of said casing whereby all of said elements are held in assembled relation.

12. A soap dispensing mechanism including a casing having an open end and a bore in the other end, a plunger slideable in said bore and having a detachable plunger head insertible through the open end of said casing, a washer having a central bore for closing the open end of said casing, a soap pumping mechanism slideable in said bore, having an operating stem extending into said bore, a pin within said casing passing through said stem, a washer adapted to bear against said plunger and holding said pin in place and held in place by said pin, a compression spring held between said first mentioned washer and said second mentioned washer, and said cylinder having a flange adapted to rest against said first mentioned washer, and said flange having a catch for engaging said casing whereby all the parts are held in assembled relation.

13. A soap dispensing mechanism comprising a casing having an outlet and a bearing, a plunger slideable within said bearing and carrying a piston, soap pumping mechanism within said casing connected to be operated by said plunger, said bearing having a groove in its side, and said plunger having an extrusion fitting within said groove constructed and arranged to admit air within said casing behind said piston and to keep said plunger from rotating.
